UNITED STATES PATENT OFFICE.

ROBERT THOMAS JENNEY, OF LONDON, ENGLAND, ASSIGNOR TO THE LAMSON CONSOLIDATED STORE SERVICE COMPANY, OF NEWARK, NEW JERSEY.

DESIGN FOR A RECEIVING-TERMINAL FOR PNEUMATIC-DESPATCH SYSTEMS.

SPECIFICATION forming part of **Design No. 33,699, dated December 11, 1900.**

Application filed August 13, 1900. Serial No. 26,794. Term of patent 14 years.

To all whom it may concern:

Be it known that I, ROBERT THOMAS JENNEY, a citizen of the United States, residing at London, England, have invented and produced a new and original Design for a Receiving-Terminal of Pneumatic-Despatch Systems, of which the following is a specification, reference being had to the accompanying drawings, forming part thereof.

Figure 1 is an elevation of a receiving-terminal of my new design, and Fig. 2 is a plan of same.

The leading features of my design comprise two curved portions with intervening flanges, a neck portion extending radially from one end of one of the curved portions, and a socket on the end of one curved portion and on the neck portion. Thus from the curved portion 1 extends the neck 2 with its

socket 3, and the curved portion 6 joins one end of the curved portion 2, there being intervening flanges 7, and there is a socket at the opposite end of said portion 6. The sides of the curved portion and the neck are ornamented by a raised pattern 10, separated by a plain portion 11.

What I claim is—

The design for a receiving-terminal of pneumatic-despatch systems, substantially as shown and described.

In testimony whereof I have hereunto set my hand in the presence of two subscribing witnesses.

ROBERT THOMAS JENNEY.

Witnesses:

EDWARD TRUMP FOSTER,
ALLEN PARRY JONES.
